UNITED STATES PATENT OFFICE.

EDWIN N. PREBLE, OF BEVERLY, MASSACHUSETTS, ASSIGNOR TO UNITED SHOE MACHINERY COMPANY, OF PATERSON, NEW JERSEY, A CORPORATION OF NEW JERSEY.

STOPPING DEVICE.

1,193,056.

Specification of Letters Patent. Patented Aug. 1, 1916.

Application filed October 30, 1912. Serial No. 728,585.

To all whom it may concern:

Be it known that I, EDWIN N. PREBLE, a citizen of the United States, residing at Beverly, in the county of Essex and State 5 of Massachusetts, have invented certain new and useful Improvements in Stopping Devices; and I do hereby declare the following to be a full, clear, and exact description of the invention, such as will enable others 10 skilled in the art to which it appertains to make and use the same:

This invention relates to stopping devices, and more particularly to stopping devices for arresting the rotation of a shaft at any 15 point in its rotary movement.

Under certain circumstances, as when the clothing or body of the operator is caught between the moving parts of a machine, it is desirable to disconnect the main driving 20 shaft of the machine from the source of power and stop the machine at once. The disconnecting of the machine from the source of power and the application of the brake, if such is employed to stop the machine, often requires the exercise of so great 25 an effort that it is practically impossible for the operator whose body or clothing is caught in the machine to stop the machine. This is particularly true in machines which 30 employ certain forms of friction clutches for connecting the main shaft with the source of power, since the members of the friction clutch are apt to stick and often require considerable force to disengage them.

35 The primary object of the present invention is to produce an emergency stopping device by which a shaft may be disconnected from the source of power and its rotation arrested at once with the exercise of 40 the least possible effort on the part of the operator.

With the above object in view one feature of the invention contemplates the provision in a stopping device of power operated 45 mechanism under the control of the operator for disconnecting the shaft from the driving mechanism at any point in the rotation of the shaft.

In the preferred form of the invention a 50 brake is employed to arrest the rotation of the shaft and the said power operated mech-

anism is arranged both to disengage the shaft from the driving mechanism and to engage the brake.

In the accompanying drawings illustrating the preferred form of the invention applied to a sole pressing machine; Figure 1 is a side elevation of the machine; Fig. 2 is a side elevation partly in section of the mechanism associated with the intermediate idle 60 pulley of the machine illustrating particularly the parts of the stop mechanism; Fig. 3 is a front elevation of the mechanism illustrated in Fig. 2, partly broken away and partly in section; Fig. 4 is a detail view in 65 vertical section illustrating certain parts of the mechanism shown in Fig. 2; Fig. 5 is a detail plan view of a portion of the mechanism illustrated in Fig. 2, showing particularly a cam supported on the intermediate 70 idle pulley and forming part of the mechanism for disconnecting the members of the driving clutch, and the mechanism for clutching the cam to the pulley; Fig. 6 is a front elevation of the mechanism illustrated in Fig. 5; and Figs. 7 and 8 are detail elevations of portions of the mechanism 75 illustrated in Fig. 2.

The sole pressing machine in which the invention, as illustrated in the drawings, has 80 been embodied, is the same in general construction and arrangement as the machine shown and described in the patent to Mayo, No. 861,746, dated July 30, 1907. This machine is a double machine, comprising two 85 sets of coöperating last and form carriers. The last carriers indicated at 1 are mounted to oscillate upon a pivot rod 2 and are connected by means of links 3 with their respective form carriers 4 which are pivoted upon 90 a pivot rod 5 extending transversely of the machine. Each set of form and last carriers is operated from a crank 6 carried by a transverse shaft 7 through a connecting link 8 which is pivotally connected with the last 95 carrier, a separate shaft 7 being provided for each set of form and last carriers. Each crank shaft 7 is provided with a worm gear 9 which is engaged by a worm 10 upon a shaft 11 journaled in bearings in the frame 100 of the machine. Each shaft 11 is provided at its rear end with a frictional clutch mem-

ber 12 secured to the shaft and with a driving pulley 13 mounted to rotate loosely on the shaft. The driving pulleys are provided with friction surfaces to engage respectively 5 the frictional clutch members 12 and means are provided for moving the pulleys longitudinally of the shafts 11 independently of each other so that each shaft 11 and crank shaft geared thereto can be driven separately. The pulleys 13 are rotated constantly by means of a single driving belt which passes over the pulleys and over an intermediate idle pulley 14 mounted upon a stud extending rearwardly from the frame 10 of the machine. The driving pulleys are moved into and out of engagement with their clutch members and their movements are controlled by mechanisms which are substantially duplicates of each other and it 15 is therefore deemed sufficient to illustrate and describe only one of such mechanisms in this application.

The driving pulley 13 at the right hand side of the machine (illustrated particularly 20 in Fig. 1) is rigidly mounted upon a sleeve 15, which is mounted to rotate loosely on the shaft 11 and is provided with a groove 16 to receive studs 17 projecting from the forked upper end of one arm of the lever 25 18-19 loosely pivoted upon a shaft 20 extending across the rear of the machine and journaled in bearings in the frame thereof. The other arm 19 of the lever 18-19 is connected by means of an adjustable link 20^a 30 with the rearwardly extending arm 21 of a lever 21-22 journaled upon a shaft 23. The construction and arrangement of the link 20^a and the lever 21-22 is such that when the arm 21 of the lever 21-22 is raised into 35 the position in which it is illustrated in Fig. 1 the clutch member 13 is moved into engagement with the coöperating clutch member 12, and when the arm 21 of said lever is moved downwardly from the position in 40 which it is illustrated in Fig. 1, the clutch member 13 is moved out of engagement with the coöperating clutch member. The arm 21 of the lever 21-22 is provided with an anti-friction roll which is engaged by a cam 24 45 secured to the rear end of a rock shaft 25 journaled in bearings in the machine frame. A treadle lever is secured to the front end of the shaft 25 by means of which the shaft 25 and the cam 24 secured thereto may be 50 rocked by the operator. The shape of the cam 24 is such that when the treadle is depressed the high part of the cam 24 is caused to engage the anti-friction roll of the lever 21-22 and raise the rear end of 55 the lever, thereby actuating the lever 18-19 to move the pulley 13 into engagement with the clutch member 12. The pulley remains locked in engagement with the clutch member until the cam 24 is oscillated in the 60 opposite direction, the shape and arrangement

of the cam 24 being such that it remains in the position in which it is placed by the operator. By the depression of the treadle at the right hand side of the machine therefore, the right hand crank shaft 7 and the 70 right hand set of last and form carriers are thrown into operation. When the cam 24 is moved in a direction to release the lever 21-22 the pulley 13 is moved out of engagement with the clutch member 12 by 75 means of a coil spring 26 attached at one extremity to the arm 22 of the lever 21-22 and at the other to the frame of the machine, and by a second coil spring 27 attached at one end to the machine frame and 80 at the other to the arm 18 of the lever 18-19.

In order to prevent the clutch members from being disengaged until the last and form carriers reach a position of presentation, a recessed disk 28 is secured to the end of the crank shaft 7 and arranged to engage a roll carried at the end of the arm 22 on the lever 21-22. The disk 28 is constructed so that while the roll on the arm 22 is in 90 engagement with the outer surface of the disk, the driving pulley 13 is held in engagement with the clutch member 12, and when the disk 28 arrives at a position such that the roll on the arm 22 drops into the 95 recess in the disk, the member 13 of the clutch is disengaged from the member 12 by the action of springs 26 and 27. The disk 28 is arranged on the crank shaft 7 in timed relation to the operation of the last 100 and form carriers so that the roll on the arm 22 drops into the recess of the said disk and the clutch members are disengaged when the last and form carriers reach a position of presentation. The cam 24 is 105 connected by a rod 29 with a second cam on the left hand side of the machine which actuates the lever corresponding to the lever 21-22 to engage the members of the driving clutch for the left hand set of last 110 and form carriers. The cams 24 are arranged so that when one treadle is depressed to throw one set of last and form carriers into operation, the other cam is actuated to release the corresponding lever 115 21-22 and cause the last and form carriers to come to rest when they have reached a position of presentation.

In order to stop the rotation of the shaft 11 as soon as the members of the driving 120 clutch have been disconnected, a brake disk 30 is secured to the shaft 11 and is arranged to be engaged by a brake shoe 31 pivoted at the central joint of a toggle, consisting of members 32 and 33, of which the member 32 is pivoted on the frame of the machine and the member 33 is pivotally connected with the arm 18 of the lever 18-19. The tension 125 of the springs 26-27 after the clutch members have been disconnected upon the arrival 130

of the last and form carriers at a position of presentation, forces the brake shoe 31 into contact with the brake disk 30.

It sometimes happens that the hand of the operator becomes caught between the form and the last, and it is then necessary, in order to prevent serious injury to the operator, to stop the machine at once as otherwise the hand of the operator will be drawn in and crushed between the form and the last. The machine embodying the present invention is provided with mechanism under the control of the operator but operated by the power by which the machine is driven for disconnecting the members of the driving clutch and stopping the machine at any point in the rotation of the shaft. This mechanism is constructed and arranged so it requires little effort on the part of the operator to set it in operation and is very quick acting so that the clutch is disconnected and the rotation of the shaft arrested almost instantly after the said mechanism is set in operation. This mechanism comprises a yoke-shaped arm 34 secured to the shaft 20 and a link 35 connecting the arm 34 with the link 20^a. The arm 19 of the lever 18-19 is provided with a slot which receives the pin connecting the link 20^a with said arm, thereby permitting the link 20^a to swing to the right about its connection with the lever 21-22. With this construction when the shaft 20 is rotated to the left (Fig. 1), the link 20^a is swung to the right about its connection with the lever 21-22, thereby causing the lever 18-19 to swing on its axis in a direction to move the pulley 13 out of engagement with the clutch member 12 and to engage the brake shoe 31 with the brake disk 30.

Power actuated mechanism controlled by the operator is provided for rotating the shaft 20 to the left when it is desired to arrest at once the rotation of the shaft 11 at any point in its rotary movement. This mechanism comprises an arm or lever fixed to the shaft 20, and a cam for actuating the lever mounted to rotate on a sleeve secured to the hub of the idle pulley 14 but normally held from rotation. A clutch device is provided for clutching the cam to the sleeve when it is desired to stop the machine. The rotation of the cam then actuates the lever fixed to the shaft 20 and the shaft is actuated to disconnect the clutch members and engage the brake.

Referring to Figs. 2 to 8 inclusive of the drawings, a lever 36 is fixed to the shaft 20 at a point substantially opposite the shaft upon which the idle pulley 14 is mounted. This lever is yoke-shaped, as illustrated in Fig. 3, the shaft 20 passing through the lower ends of the arms of the yoke. A roll 41 is mounted between lugs 42 formed on the lever 36 and is arranged to engage a

cam shaped flange 43 formed on a member 44. The member 44 is provided with a supporting ring 45 which is loosely mounted on a sleeve 46 secured to the hub of the idle pulley 14 by a set screw 47. To prevent the ring 45 from sliding axially of the sleeve, the ring is confined between an abutment formed on the sleeve and a ring 48 threaded on the end of the sleeve. This construction permits the sleeve 46 to rotate freely within the ring 45 while the member 44 is held stationary. When the member 44 is caused to rotate in a right hand direction (Fig. 6) with the pulley 14, the lever 36 will be swung to the left (Fig. 2) by the engagement of the roll 41 with the cam flange 43 and turn the shaft 20 in a direction to disengage the clutch members 12 and 13 and apply the brake to stop the machine.

In order to clutch the member 44 to the sleeve 46 and cause it to turn with the idle pulley, a flange 49 is formed on the sleeve 46 and constitutes one member of a clutch, the other member of which consists of a clutch shoe 50 pivoted on a rod or shaft 51 between the arms 52 of a member 53. The member 53 in turn is pivoted on a rod or shaft 54 supported by downwardly and rearwardly extending arms 55 on the member 44 and passing through the ends of the arms 52 which extend upwardly and rearwardly as illustrated in Fig. 2. The member 53 is thus pivoted and the clutch shoe 50 is supported thereby so that when the forward portion of said member is lifted, the clutch shoe will be engaged with the flange 49 to clutch the member 53 and the member 44 upon which the member 53 is mounted to the sleeve 46, and cause the member 44 to rotate with the pulley 14. The member 44 and the member 53 connected therewith are normally held from rotation with the sleeve 46 by a coiled spring 53^a connected at one extremity with the member 53 and at the other with a fixed point on the machine frame. To provide for supporting the member 53 in the position illustrated in Fig. 2 with relation to its pivotal point, a cylindrical flange 56 is formed on said member 53, the outer surface of which is substantially co-axial with the axis of the pulley 14 and the forward portion of the member 53 is supported by the engagement with said flange of a roll 57 mounted on a yoke 59 pivoted on a bracket 60 secured to the machine frame. A second roll 61 is mounted in the yoke 59 and rests on a table 62 formed on an arm 63 pivoted on a shaft 64 carried by forwardly projecting ears 65 on the lever 36. The arm 63 is supported by a link 66 which connects said arm with a rearwardly projecting arm 67 formed on a lever 37 loosely mounted on the shaft 20 between the arms of the lever 36 and extending upwardly between the arms of said lever to a point adjacent its upper end. The link 130

4

66 is connected with the arm 67 by a shaft 68 and the link is provided with a slot, as illustrated in Fig. 2, through which the shaft passes. A plunger 69 actuated by a coil spring 70 is mounted in the link 66 and engages the shaft 68 and normally supports the link with the shaft 68 at the lower end of the slot, thereby providing a yielding support for the table 62. A pull rod 71 is pivotally connected with the upper end of the lever 37 and is provided with a handle at the front of the machine which may be gripped by the operator. When the lever 37 is swung to the left about the shaft 20 with relation to the lever 36, the movement of the arms 67 acting through the link 66 will lift the table 62, the outer end of the yoke 59 and the forward portion of the member 53. During the normal operation of the machine, the parts of the above described mechanism occupy the positions illustrated in Figs. 2 and 3, the sleeve 46 turning freely within the ring 45 of the member 44 without affecting said member. When it is desired to stop the machine at once, the operator grasps the handle on the pull rod 71 and gives a slight forward pull on said rod, thereby swinging the lever 37 about the shaft 20. A latch 38 is pivoted at 39 on the upper end of the lever 36 and normally rests on the upper face of a shoulder or projection 40 on the upper extremity of the lever 37. This movement of the lever 37 causes the latch 38 to drop behind the shoulder 40 and lifts the table 62 and the arm 59 causing the member 53 to swing about the shaft 54 to engage the clutch shoe 50 with the flange 49. The member 44 is thereby clutched to and caused to rotate with the sleeve 46. The turning of the cam flange 43 swings the lever 36 to the left (Fig. 2), which rotates the shaft 20 in a direction to disengage the members of the driving clutch and engage the brake to stop the machine. By reason of the engagement of the latch 38 behind the shoulder 40, the lever 37 is caused to swing with the lever 36. When the shaft 20 has been rotated sufficiently to disengage the clutch members and engage the brake, the latch 38 is lifted from behind the shoulder 40 by the engagement of an upwardly projecting arm on said latch with an adjustable stop screw 72 mounted on the frame of the machine. After the latch 38 is lifted from behind the shoulder 40, the lever 36 swings to the left a slight distance independently of the lever 37 and the table 62 is thereby lowered sufficiently to disengage the clutch shoe 50 from the flange 49. The member 53 and the mechanism connected therewith are then restored to the positions illustrated in Figs. 2 and 3 by the spring 53^a. The driving clutch members are, however, held in disengagement until the operator grasps the pull rod and actuates the

same to restore the levers 36 and 37 to the positions illustrated in Fig. 2. A stop screw 73 is threaded into a lug 74 on the lever 37 and engages a lug 75 on the lever 36 to cause the lever 36 and the shaft 20 to swing with the lever 37 when the rod 71 is actuated to restore the parts to their normal positions.

A very slight effort is required to throw the above mechanism for disconnecting the clutch members into operation and the rotation of the shaft is arrested and the machine stopped almost instantly after the actuation of the pull rod. The actuation of the power disconnecting mechanism by the power by which the machine is driven also renders this mechanism much more certain and reliable than mechanisms which are actuated by the operator.

Although the invention has been illustrated and described as applied to a sole pressing machine, it is to be understood that the invention is not limited to such a machine but may be applied with advantage to various machines. It is also to be understood that except as defined in the claims the invention is not limited to any particular construction or arrangement of parts.

Having explained the nature and object of the invention and having specifically described the preferred embodiment thereof, what is claimed is:

1. A stop mechanism, having, in combination, a shaft, driving mechanism for the shaft, means acting normally to maintain the driving mechanism in driving connection with the shaft until the shaft has executed a predetermined rotary movement after the driving mechanism has been connected therewith, and then to permit the driving mechanism to be disconnected from the shaft and mechanism actuated by the power by which the shaft is driven when thrown into action to disconnect the driving mechanism from the shaft at any point in the rotation of the shaft.

2. A stop mechanism, having, in combination, a shaft, driving mechanism for the shaft, devices for arresting the rotation of the shaft, and means constructed and arranged to be actuated at once by the power by which the shaft is driven when thrown into action to disconnect the driving mechanism from the shaft and engage the arresting devices to stop the shaft at any point in the rotation of the shaft.

3. A stop mechanism, having, in combination, a shaft, driving mechanism for the shaft, means acting normally to maintain the driving mechanism in driving connection with the shaft until the shaft has executed a predetermined rotary movement after the driving mechanism has been connected therewith, and then to permit the driving mechanism to be disconnected from the shaft and power operated mechanism

- under the control of the operator for throwing the driving mechanism out of driving connection with the shaft at any point in the rotation of the shaft.
- 5 4. A stop mechanism, having, in combination, a shaft, a driving clutch member, a driven clutch member, means acting normally to maintain the clutch members in engagement until the shaft has executed a predetermined rotary movement after the clutch members are engaged, and then to permit the clutch members to be disengaged and power operated mechanism under the control of the operator for disengaging the clutch members and stopping the shaft at any point in the rotation of the shaft.
- 10 5. A stop mechanism, having, in combination, a shaft, driving mechanism for the shaft, a brake, and mechanism under the control of the operator and operated by the power by which the shaft is driven for throwing the driving mechanism out of driving connection with the shaft and engaging the brake to stop the shaft at any point in the rotation of the shaft.
- 15 6. A stop mechanism, having, in combination, a shaft, driving mechanism for the shaft, means to prevent the driving mechanism from being thrown out of driving connection with the shaft except at a definite point in the rotation of the shaft and mechanism under the control of the operator and operated by the power by which the shaft is driven for throwing the driving mechanism out of driving connection with the shaft at any point in the rotation of the shaft.
- 20 7. A stop mechanism, having, in combination, a shaft, a driving clutch member, a driven clutch member, a brake, and mechanism under the control of the operator and operated by the power by which the shaft is driven for disengaging the clutch members and engaging the brake to stop the shaft at any point in the rotation of the shaft.
- 25 8. A stop mechanism, having, in combination, a shaft, driving mechanism for the shaft, means acting normally to maintain the driving mechanism in driving connection with the shaft until the shaft has executed a predetermined rotary movement after the driving mechanism has been connected therewith, and then to disconnect the driving mechanism from the shaft power operated mechanism for throwing the driving mechanism out of driving connection with the shaft at any point in the rotation of the shaft, and means under the control of the operator to throw said last mechanism into operation.
- 30 9. A stop mechanism, having, in combination, a shaft, a driving clutch member, a driven clutch member, mechanism acting normally to maintain the clutch members in engagement until the shaft has executed a predetermined rotary movement after the clutch members are engaged, and then to disconnect the clutch members and stop the shaft at any point in the rotation thereof comprising a normally stationary cam, means under the control of the operator to cause the actuation of the cam by power and mechanism actuated by the cam to disconnect the clutch members and stop the shaft.
- 35 10. A stop mechanism, having, in combination, a shaft, a driving clutch member, a driven clutch member, mechanism acting normally to maintain the clutch members in engagement until the shaft has executed a predetermined rotary movement after the clutch members are engaged a constantly rotating member, means to disconnect the clutch members to stop the shaft comprising a normally stationary cam, means under the control of the operator to clutch the cam to the constantly rotating member, and mechanism actuated by the cam to disconnect the clutch members.
- 40 11. A stop mechanism having, in combination, a shaft, driving mechanism for the shaft, devices for arresting the rotation of the shaft, means actuated by the power by which the shaft is driven when thrown into action to disconnect the driving mechanism from the shaft and engage the arresting devices to stop the shaft at once, and mechanism under control of the operator for throwing said means into action at any point in the rotation of the shaft.
- 45 12. A stop mechanism, having, in combination, a shaft, driving mechanism for the shaft, means acting normally to maintain the driving mechanism in driving connection with the shaft until the shaft has executed a predetermined rotary movement after the driving mechanism has been connected therewith and then to disconnect the shaft from the driving mechanism, and mechanism actuated by the power by which the shaft is driven when thrown into action to disconnect the driving mechanism from the shaft at any point in the rotation of the shaft.
- 50 13. A stop mechanism, having, in combination, a shaft, driving mechanism for the shaft, devices for arresting the rotation of the shaft, means acting normally to maintain the driving mechanism in driving connection with the shaft until the shaft has executed a predetermined rotary movement after the driving mechanism has been connected therewith and then to disconnect the shaft from the driving mechanism, and engage the arresting devices to stop the rotation of the shaft, and means actuated by the power by which the shaft is driven when thrown into action to disconnect the driving mechanism from the shaft and engaging the

arresting devices to stop the shaft at once at any point in the rotation of the shaft.

14. A stopping mechanism, having, in combination, a shaft, driving mechanism for the shaft, positively operating means acting normally to maintain the driving mechanism in driving connection with the shaft until the shaft has executed a predetermined rotary movement after the driving mechanism has been connected therewith, and

mechanism actuated by the power by which the shaft is driven when thrown into action to disconnect the driving mechanism from the shaft at any point in the rotation of the shaft.
